UNITED STATES PATENT OFFICE.

SAMUEL AUGUSTUS JONES, OF WASHINGTON, DISTRICT OF COLUMBIA.

NURSING-BOTTLE DESIGNED FOR USE WITH RUBBER NIPPLES.

1,118,134.

Specification of Letters Patent. Patented Nov. 24, 1914.

Application filed June 22, 1911. Serial No. 634,671.

To all whom it may concern:

Be it known that I, SAMUEL AUGUSTUS JONES, a citizen of the United States, residing at Washington, in the District of Columbia, have invented certain new and useful Improvements in Nursing-Bottles Designed for Use with Rubber Nipples, of which the following is a specification.

My invention relates to an improvement 10 in glass nursing bottles from which the contents are withdrawn through a rubber nipple fitting over the top and neck of the bottle, the improvement consisting in providing a minute duct or passageway of uniform cross 15 sectional area whereby air is admitted in sufficient quantity to replace the contents withdrawn by suction through the opening provided in the nipple.

The essential and peculiar feature which 20 distinguishes my improvement from other devices of a similar nature lies in restricting the cross sectional area of the duct or passage along its entire length, and extending it 25 for a considerable distance under the confining surface of the nipple. The result obtained by this construction and arrangement is to set up, in the said duct or passage, a sufficient amount of frictional resistance between 30 the contained liquid and the walls of the passage, to neutralize the interior pressure or weight of liquid tending to cause leakage.

The invention is illustrated in the accompanying drawings in which—

Figure 1 shows the neck, flange and mouth 35 of a nursing bottle "A" with a minute groove "C" of uniform cross section which passes from the mouth or opening of the bottle on the surface of the body and side of the flange and downward on the outer surface of the 40 neck about $\frac{1}{4}$ inch, so as to be below the lower margin of the body of an applied rubber nipple. Fig. 2 shows a sectional view of the upper part of the nursing bottle "A" indicating the course of the groove "C" on the 45 outside surface of the flange and neck. Fig. 3 is the same as Fig. 1 except that it shows a rubber nipple "B" applied, converting the groove "C" into a minute tube. Fig. 4 shows a sectional view similar in all respects 50 to Fig. 2 except for the addition of nipple

"B" showing the conversion of the groove "C" into a tube.

Referring to the drawings A is the neck of an ordinary nursing bottle and B the rubber cap or nipple formed to be fitted 55 thereover and to closely embrace its surface.

C is a duct or passageway formed in the upper face and side of the neck A. This groove is of a very restricted cross sectional area and is of the same size along its entire 60 length, and follows the contour of the surface of the bottle in such manner that when the rubber nipple is applied a continuous tube will be formed leading under the surface of said nipple and from the outside air 65 to the interior of said bottle.

I have found that a duct formed as above will admit sufficient air to equalize the pressure set up when the contents of the bottle are removed by suction, as when a child is 70 nursing, and that the frictional resistance exerted between the walls of the duct and the contained liquid will prevent leakage under varying pressure conditions and in any position of the bottle. The duct should not be 75 larger than one-fiftieth of an inch in width and depth to secure reliable results, and it should extend about three quarters of an inch along the face of the bottle neck up to and over the flange, continuing along its 80 entire course of the same width, depth and consequent sectional area. The continuation of the groove from the opening of the bottle to the upper and outer edge of the flange is necessary to prevent the rubber nipple from 85 collapsing down at that point and blocking the upper end of the duct. A duct formed in this manner will permit sufficient air to enter the bottle and will not permit the outflow of the contained liquid.

I am aware that various devices including grooves have been used in connection with nursing bottles for the purpose of restoring the pressure equilibrium and do not claim this broadly as my invention.

What I claim and desire to secure as Letters Patent is:

In combination with a nursing bottle and a rubber nipple therefor, a small groove, of uniform dimensions throughout, passing up- 100

ward in the outer surface of the neck and over the flange to the mouth or opening, forming with the applied body of the nipple a small calibered, crooked and relatively long duct or passage connecting the cavity of the nipple and bottle with the outer air.

In testimony whereof I affix my signature in presence of two witnesses.

SAMUEL AUGUSTUS JONES.
